Application February 19, 1934, Serial No. 711,846

8 Claims. (Cl. 89—3)

The general object of the present invention is to provide an automatic firearm or machine gun which is simple in construction, reliable in operation, of light weight and capable of sustained 5 operation without excessive heating. A gun embodying the invention is of the gas operated type, the barrel being normally rigidly connected with the breech casing.

In accordance with the invention the cartridge 10 feed channel is below the barrel, and the cartridges are fed by means of a slide positioned below the feed channel and above the gas actuated operating slide.

Further in accordance with the invention I 15 provide an improved means for transferring the cartridges from the feed channel to the chamber of the barrel and improved means for ejecting the empty shells.

In the accompanying drawings I have shown 20 one embodiment of the invention, but it will be understood that the drawings are for illustrative purposes only and are not to be relied upon as limiting or defining the scope of the invention, the claims forming a part of this specification 25 being relied upon for that purpose.

Of the drawings:

Fig. 1 is a side view of a firearm embodying the invention.

Fig. 2 is an enlarged fragmentary view of the 30 rear portion of the firearm, this view being partly a side view and partly a longitudinal sectional view.

Fig. 3 is a view similar to Fig. 2, but showing the parts in different relative positions.

Fig. 4 is an enlarged fragmentary view of the 35 front end of the firearm, this view being partly a side view and partly a longitudinal sectional view.

Fig. 5 is a view similar to Fig. 4, but showing 40 the parts in different relative positions.

Fig. 6 is a fragmentary perspective view of the rear portion of the barrel.

Fig. 7 is a transverse sectional view taken along the line 7—7 of Fig. 4.

Fig. 8 is an enlarged sectional view of the front 45 buffer means for the operating slide.

Fig. 9 is a transverse sectional view taken along the line 9—9 of Fig. 2.

Fig. 10 is a perspective view showing the ex- 50 tractor and associated parts.

Fig. 11 is an enlarged fragmentary horizontal 55 sectional view taken along the line 11—11 of Fig. 1.

Fig. 12 is a view similar to Fig. 11, but showing 55 the parts in different relative positions.

Fig. 13 is a plan view of the operating slide, together with a part of the piston rod.

Fig. 14 is a side view of the parts shown in Fig. 13.

Fig. 15 is a perspective view of the feed slide. 5

Fig. 16 is a transverse sectional view taken along the line 16—16 of Fig. 12.

Fig. 17 is a view taken along the line 17—17 of Fig. 11 and showing in detail the extractor and the cam mechanism which operates it. In this 10 view the extractor, the pressure lever for the extractor and the cam mechanism are shown in full lines and all other parts are shown in dot-and-dash lines.

Figs. 18, 19 and 20 are views similar to Fig. 15 17, but showing the parts in different relative positions.

Referring to the drawings, I represents as an 20 entirety the main breech casing which is generally rectangular in section as shown in Fig. 9. As 25 shown the casing is formed from a single piece of steel although I do not necessarily limit myself to this integral construction. The portion 1^a of the casing is formed to receive the rear end of a barrel 2. Behind the portion 1^a are two main 25 side walls 1^b, 1^b connected at the rear by an integral top wall 1^c. An opening 1^d is provided in the top wall, which opening is normally closed by a pivoted cover 3 held by a releasable latch 4. The bottom of the casing is normally closed 30 by separate plates 5 and 5^a. The rear of the casing is normally closed by a plate 6 flanged at its sides and having ribs (not shown) adapted to enter grooves 7, 7 (see Fig. 11) formed in the side walls 1^b, 1^b. A suitable latch (not shown) 35 serves to normally hold the end plate 6 in place. Carried by the plate 6 at opposite sides thereof are two brackets 8, 8 carrying handles 9, 9.

The barrel 2 is preferably detachably connected 40 with the casing and has a rear cylindrical portion 2^a which fits a cylindrical hole in the portion 1^a of the casing. The rear end of the barrel is provided at 10 with interrupted external threads adapted to engage similar internal threads formed 45 in the casing. When the barrel is in the position shown in Figs. 2 and 3 it is firmly held in place by the threads. It can be released by being turned through a quarter turn in the clockwise direction.

The barrel is normally held in its locked position 50 by means of a pin 11 held by a spring 12. The rear end of the spring is T-shaped and fits a T-shaped groove 13 in the top of the casing, and a screw 14 normally serves to prevent the spring from moving rearward out of the T-shaped 55 slot. The pin 11 can be withdrawn from the

hole in the barrel by means of a suitable tool such as the head of a cartridge and then the barrel can be turned in the clockwise direction to disengage the interrupted threads at 10. This permits the barrel to be drawn out in the forward direction. In order to avoid the necessity for using a tool to replace the barrel, the barrel is provided as shown in Figs. 6 and 16 with a longitudinal groove 15 positioned to receive and provide clearance for the pin 11. The groove 15 has a beveled surface 15^a adjacent its forward end, which surface serves to cam the pin 11 outward when the barrel is moved in the counter-clockwise direction into locking position. As soon as locking position is reached the pin 11 snaps into the hole in the barrel, thus firmly locking it. The barrel 2 is preferably provided with a series of annular ribs 2^a, 2^b to facilitate cooling. As already explained the barrel is readily removable, and if excessive heating eventually occurs the gun may be kept in service by removing one barrel and substituting another.

The casing 1 is provided with an integral extension 1^a which extends forward underneath the barrel. This extension is hollow and it serves to engage and retain a piston tube 16. The tube 16 is preferably slidable longitudinally with respect to the casing, and movement in the forward direction is limited by a shoulder 17 on the tube 16 which engages a shoulder 18 on the casing. At its forward end the tube is connected with and supported by the barrel. Preferably the tube is provided at the top thereof with a T-shaped projection 19 which fits a similarly shaped T-slot formed in a band 20 secured to the barrel. With the parts engaged as shown in Figs. 4 and 7 the tube is held in rigid relationship to the barrel, but by moving the tube rearward it is disengaged from the barrel as shown in Fig. 5, thus leaving the barrel free to be turned so that it may be disengaged from the casing in the manner already explained.

The tube 16 is normally held in its forward engaged position by means of two links 21 and 22 which are pivotally connected with each other by a pin 23. Preferably the link 21 is U-shaped in cross section so as to partly surround and enclose the link 22. The link 21 is pivoted to the front end of the portion 1^a of the casing by means of a removable pin 24, and the link 22 is pivoted to the tube 16 by means of a pin 25. A spring pressed latch 26 is provided for holding the link 21 in its upper or normal position. It will be observed that with the parts in the positions shown in Fig. 4 the tube 16 is held in its forward position, the link 21 substantially enclosing the link 22. When it is desired to move the tube 16 in the rearward direction the link 21 is disengaged from the latch 26 and the link is moved downward to the position shown in Fig. 5, thus drawing the tube rearward and disengaging the projection 19 from the T-slot in the band 20.

Longitudinally movable along the bottom of the main casing is an operating slide 27, this slide being connected with a piston rod 28 and a piston 29 positioned within the piston tube 16. Preferably the piston 29 is formed integrally with the rod and consists of one or more annular flanges thereon. A cylinder 30 is provided in the forward end of the tube 16, being held in place by threads, and the piston 29 accurately fits the said cylinder. A series of registering gas holes connect the bore of the barrel 2 with the interior of the cylinder 30 in order that a portion of the gases

of explosion may enter the cylinder and act upon the piston 29 to force it rearward.

For returning the slide in the forward direction after having been moved rearward by the piston and piston rod, there is provided an action spring 31 supported upon and guided by a rod 32. Preferably the spring and rod 31 and 32 extend into a hollow buffer 33 carried by the rear plate 6. The spring at its rear end abuts against a head 34 detachably secured in place in the buffer. The spring at its forward end extends into an aperture in the slide 27 and abuts against a shoulder 35. A hole 36 provides clearance for the rod 32 when the slide is in its rear position.

When the slide moves forward under the influence of the spring 31 its movement is limited by a suitable buffer which surrounds the piston rod 28, an enlarged sectional view of this buffer being shown in Fig. 8. The rear portion of the piston tube 16 is formed with a cylindrical recess 20 in which is positioned a split bushing 37 which very loosely fits the opening. The inner surface of the split bushing 37 is tapered and it engages the outer surface of a similarly tapered bushing 38. A removable screw 39 serves to hold the two bushings in place. It will be observed that when the slide 27 moves forward it engages the inner bushing 38 which is forced into the outer bushing 37. This outer bushing by reason of the fact that it is split and is resilient offers friction which resists and stops the forward movement of the slide. When the slide again moves rearward the inner bushing 38 follows it until limited by the screw 39, the bushing thus being ready to be engaged by the slide upon its next forward movement.

In order to provide a further means for absorbing the energy of the slide at the end of its forward movement, provision may be made for permitting the entire tube 16 to move longitudinally through a slight distance. As shown there is provided a spring pressed plunger 40 carried by the front end portion of the casing which abuts against the shoulder 17 on the tube. In order to permit limited movement of the tube 16 the link 21 is provided with elongated holes for receiving the pivot pin 24. From the foregoing description it will be observed that the energy of the slide is absorbed in part by the two coating bushings 37 and 38 and in part by the plunger 40. The plunger serves to return the piston tube 16 to its normal position as shown in Fig. 4 after it has been moved forward as the result of the blow delivered by the slide.

The plunger 40 not only serves as a buffer to absorb the energy of the slide, but it also serves to permit or cause sharp vibratory movements of the piston tube which tends to break loose any deposits which might otherwise tend to form in the cylinder 30 or on the guide surfaces at 19. With some types of ammunition these deposits become seriously objectionable and the vibratory movement which I have provided assists in preventing the accumulation and adherence of such deposits.

The slide 27 serves to operate the feeding, loading and firing mechanisms of the gun and these mechanisms will now be described in detail.

Extending transversely through the casing below the rear portion of the barrel is a cartridge feed channel 41 adapted for the reception of a cartridge belt, such as A. The channel 41 is sufficiently wide at the left hand side of the gun to permit the entry of cartridges, but preferably its width is only slightly greater than the length of

the cartridges. At the right hand side the feed channel is much narrower, being only wide enough to permit the exit of the canvas belt which carries the cartridges. Below the cartridge channel 41 and above the slide 27 are two opposite transverse ribs 42, 42 which form guiding means for a feed slide 43. The feed slide with its appurtenances is in some respects similar to that disclosed in Patent No. 1,293,021 to John M. Browning.

At the top of the slide 27 there is provided a cam path which is preferably in the form of a cam groove 44 cut in the top surface of the slide. At least a portion of this groove 44 is inclined with respect to the longitudinal movement of the slide, and as shown the cam path also has a longitudinal rear portion 44a and a longitudinal forward portion 44b. On the bottom of the feed slide 43 there is provided means such as a pin 45 for engaging the cam path or groove 44. The feed slide should be made as light in weight as strength requirements will permit, the object of this being to keep the total mass of the moving parts actuated by the operating slide as small as possible so as to obtain maximum speed of operation and to reduce the total weight of the firearm. By forming the cam groove 44 in the operating slide and providing the feed slide with the pin 45 the width of the feed slide can be reduced to that necessary for proper feeding of the cartridges. As shown, the feed slide is substantially less in width than the cartridge feed channel 41. When the slide 27 is in its rearmost position as shown in Fig. 11 the feed slide 43 is at the left hand limit of its movement; and when the operating slide 27 is in its forward position as shown in Fig. 12 the feed slide is at the right hand limit of its movement. Thus longitudinal movement of the operating slide 27 serves to cause transverse movement of the feed slide 43. Carried by the feed slide 43 is a pivoted pawl 46 which is adapted to engage the successive cartridges of the belt A to feed the said belt from left to right during the movement of the feed slide from left to right. The pawl 46 is provided with a tail piece 46a which underlies and helps to support the cartridge which is engaged. During movement from right to left the pawl 46 passes under the next following cartridge and then snaps upward in position to engage it. A pawl 47 carried by the casing serves to prevent outward movement of the feed belt.

Preferably the slide 27 and the parts associated therewith are removable from the firearm at the rear thereof. To effect such removal it is necessary first to remove the spring 31 and the rod 32 and to then remove the end plate 6 with the parts carried thereby. The slide is then free to be withdrawn in the rearward direction except for the fact that the pin 45 is engaged in the cam groove 44. In order to permit the rearward removal of the cam slide, provision is made to permit the cam engaging means on the feed slide, that is, the pin 45, to be disengaged from the cam path, that is, from the groove 44. This disengagement may be effected in different ways, but I have shown the groove 44 as having a transversely unobstructed portion or opening 48. During the normal reciprocation of the slide 27 the unobstructed portion or opening 48 does not come into register with the pin 45, but by moving the slide rearward slightly beyond its normal limit of movement the opening 48 is brought into register with the pin 45, thus permitting the pin 75 and slide to be moved transversely sufficiently to

be disengaged from the cam groove 44. In order to permit this transverse movement the adjacent wall of the casing below the feed slide is provided with a notch 48a to provide clearance for the pin 45. With the pin 45 thus disengaged from the cam groove the slide can be readily withdrawn rearward.

Preferably the feed slide 43 is entirely removable from the firearm, being normally held in place solely by reason of the engagement of the pin 45 with the groove 44. So long as the operating slide 27 remains within its normal range of movement the feed slide 43 is held and removal thereof is prevented. However, when the operating slide is moved sufficiently to bring the opening 48 into register with the pin 45 the feed slide can then be entirely removed from the firearm.

The firearm is provided with a reciprocating breech bolt 49 having lateral guide ribs 49a, 49b which enter longitudinal grooves in the side walls 1b, 1b of the casing and thus guide the breech bolt for longitudinal movement. The breech bolt is operated and controlled by mechanism operated by the slide 27, this mechanism being similar to that disclosed in Patent No. 1,293,022 to John M. Browning. As shown in Fig. 2 the breech bolt 49 is connected with the slide 27 by means of two links 50 and 51 pivotally connected with each other at 52. The link 50 is pivotally connected with the breech bolt at 53 and the link 51 is pivotally connected with the slide at 54. When the slide 27 is in its rear position as shown in Fig. 2, the two links 50 and 51 are substantially in alignment and an extension 50a on the link 50 engages the top wall 1c of the casing to hold the links in the relative positions shown.

When the slide 27 moves forward under the influence of the action spring 31 the two links 50 and 51 and the breech bolt 49 move in unison with it until the breech bolt nearly reaches its forward position, the link 50 being then approximately in register with the opening 1d in the top wall of the casing. At or about the time that the link comes into register with the opening the curved portion 50b of the link 50 engages two cams 55 projecting inward from the respective side walls 1b, 1b of the casing. In the drawings only the cam on the left hand side is clearly shown, but it will be understood that there is a similar cam on the right hand side. These cams 55 cooperate with the curved portion 50b of the link 50 to force the link upward into the opening 1d, the rear end portion of the link abutting against the rear wall of the opening as clearly shown in Fig. 3. In the meantime the slide 27 has continued its forward movement, thus bringing the link 51 into a substantially upright position. With the parts in the position shown and described, the breech bolt is firmly locked in its forward or breeched position and is well adapted to resist the recoil action incident to firing. Following firing the slide 27 is moved rearward by the action of the gases of explosion in the manner already described, the link 51 then serving first to draw the link 50 downward out of locking position and then to move the link 50 and also the bolt 49 rearward to the positions shown in Fig. 2.

Reference has already been made to the fact that the slide 27 can be removed through the rear of the casing. It will be understood that the breech bolt 49 and the links 50 and 51 are sim- 75

ilarly removable, all of these parts being removable as a unit.

A firearm incorporating the present invention is intended to be used with cartridges having annular grooves in the heads thereof, and the front end of the breech bolt is provided with vertical ribs 56, 57 which cooperate to form a vertical groove for receiving and retaining the heads of the cartridges. When the breech bolt is in its forward position as shown in Fig. 3 the head of the cartridge which is in central position in the feed channel 41 is vertically below the groove in the front of the breech bolt. For withdrawing the cartridge from the feed channel and lifting it into proper relationship to the breech bolt there is provided an extractor 58 shown in detail in Fig. 10. This extractor is provided with a pivot pin 59 which fits a transverse pivot opening in the breech bolt, the extractor thus moving bodily rearward and forward as the breech bolt moves. The extractor 58 is provided with a transversely extending tooth 60 which is so shaped and positioned as to enter the groove in the cartridge when the breech bolt and the extractor are in their forward positions as shown in Fig. 3. For pressing the forward end of the extractor upward so as to hold the tooth 60 in firm engagement with the cartridge, there is provided a pressure lever 61 pivoted to the breech bolt and engaging at its forward end with the extractor. A coil spring 62 tends to move the pressure lever 61 in the counter-clockwise direction, thus pressing the forward end of the extractor upward.

A suitable cam mechanism is provided for controlling and guiding the relative movements of the extractor and preferably this mechanism is located at the left side of the firearm. For convenience of construction the left side wall 1^b is cut away to provide an opening 63 as shown in Fig. 2 and this opening is covered by a plate 64, shown in Figs. 11 and 12. The cam mechanism to be now described is carried by the plate 64 and projects inward through the opening 63.

The extractor 58 is provided with a pin 65 which projects toward the left and which serves as a means for controlling the upward and downward movements of the extractor. Preferably this pin is spring pressed outward so as to provide frictional engagement at its end with the surface of the cam plate 64. When the breech bolt moves rearward from the position shown in Fig. 3 the extractor 58 withdraws the cartridge with which it is engaged and the extractor is moved upward by the lever 61. Thereafter as shown in Fig. 17 the pin 65 engages a cam surface 66 on the plate 64 which forces the pin upward and thus causes continued upward movement of the extractor. Thus the cartridge is moved not only rearward but also upward. Continued rearward movement brings the parts into the relative positions shown in Fig. 2, the pin 65 being retained between two cam walls and the cartridge being lifted nearly to its firing level.

The cam plate 64 carries a pivoted cam member 67 which is normally spring pressed to the position shown in Figs. 2, 18 and 20. However, the pin 65 in moving rearward passes under the rear portion of the cam member 67 and lifts it as shown in Fig. 17. When the parts move forward from the position shown in Fig. 2, the pin 65 moves along the top of the cam member 67 as shown in Fig. 18, thus further lifting the cartridge so that it is brought into exact alignment 75 with the chamber in the barrel. As forward

movement continues the cartridge is pushed into the chamber in the barrel as shown in Figs. 19 and 3.

When the cartridge has been sufficiently entered in the chamber to be retained thereby, the extractor 58 is withdrawn from it, the pin 65 engaging the cam surface 66 as shown in Fig. 19 and being pushed downward. In order to support the rear end of the cartridge and to prevent it from moving downward with the extractor, there is provided a resiliently held detent 68 pivoted in a slot in the bolt 49. This detent is pressed in the forward direction by a spring plunger 70, and it thus snaps under the cartridge to support it.

As forward movement continues to the position shown in Fig. 20, the extractor is moved still further downward, the pin 65 being disengaged from the cam members and the extractor being held directly by the cam surface 71. As the extractor reaches the position shown in Fig. 20, which is the same position shown in Fig. 3, the tooth 60 engages the next cartridge and the parts are in positions for a repetition of the loading operation which has just been described.

With the parts in the positions shown in Figs. 3 and 20, firing is automatically effected by means to be presently described and the parts again move in the rearward direction. The shell of the cartridge which has just been fired is still held in the groove in the front face of the bolt and this shell is drawn rearward as the bolt moves rearward. When the new cartridge from the feed channel is moved rearward and upward in the manner already described, it engages the empty shell of the preceding cartridge and moves it upward to the position shown at B in Fig. 9. As shown in Fig. 9 the right hand rib 57 forming the cartridge groove extends to the top of the bolt, but the left hand groove 56 terminates below the top of the groove. When a cartridge has been moved to the position indicated at B it is still in engagement with the right hand groove 57, but it is above and out of engagement with the left hand groove 56. At the top of the bolt 49 and at the left side thereof there is provided an ejector 72 normally held by a spring 72^a in its rearward position with respect to the bolt as shown in Fig. 12. The ejector 72 is connected to the bolt by means of a stud on the bolt extending through a slot in the ejector. In its normal position the ejector is not engaged by the shell as it moves upward to position B, but preferably the ejector has a hook portion 73 which is vertically above the shorter rib 56 on the bolt. It will thus be seen that as the shell is moved upward to the position B it is adapted to be engaged partly by the upper end of the rib 57 and partly by the hook portion 73 of the ejector 72. Carried by the casing at the left side thereof is a pin 74 which is in position to engage a stud 75 projecting from the ejector. Just before the breech bolt reaches its extreme rearward position the pin 74 engages the stud 75 and moves the ejector relatively forward with respect to the bolt as shown in Fig. 11, thus throwing the cartridge shell toward the right to the position B' shown in Figs. 2 and 11. An ejection opening 76 is provided in the right wall of the casing and the shell is thus thrown out through this ejection opening.

Preferably the pin 74 is carried by a spring 77 secured to the left side wall of the casing. This spring mounting for the pin 74 enables the pin to be withdrawn so as to avoid interference when 75

the breech bolt and other parts are to be removed through the rear of the casing. The spring has the further advantage of providing a limited resilience which avoids excessive shock incident to the ejection operation.

I have referred to the lifting of the cartridge shell to the position B by the action of the next following cartridge. It is necessary, however, to eject the last cartridge that is to be fired, that is, the last cartridge in the cartridge belt, and in order that this last cartridge may be properly lifted to ejection position I preferably avoid complete dependence upon the next following cartridge as the lifting means. As clearly shown in Fig. 10, a lifter 78 is pivotally mounted on the extractor 58, the said lifter being shaped to fit around the cartridge that is being moved by the extractor and the said lifter having an upper surface 79 adapted to engage the cartridge shell to be lifted and ejected. This lifter cooperates with the next following cartridge, if there be one, to lift the shell to the level B, and if there be no next following cartridge the lifter serves in and of itself to so lift the shell. The lifter 78 is resiliently held and as the extractor moves downward again as shown in Fig. 19 the lifter yields laterally.

Mounted in the breech bolt is a firing pin 80 biased in the forward direction by means of a spring 81. Pivoted on the breech bolt is a sear 82 adapted to engage a shoulder 83 on the pin as shown in Fig. 2. A spring pressed plunger 84 serves to bias the sear toward its operative position. The firing pin 80 is provided with a shoulder 85 which is adapted to be engaged by a shoulder 86 on the slide 27. From the description which has already been presented, it will be understood that the slide 27 moves rearward to a greater extent than does the breech bolt 49 and it will, therefore, be evident that in moving from the position shown in Fig. 3 to the position shown in Fig. 2 the shoulder 86 will engage the shoulder 85 to move the firing pin 80 relatively rearward into its cocked position so that it can be engaged and held by the sear 82. As the parts move forward from the position shown in Fig. 2 to the position shown in Fig. 3 the lower tail portion of the sear 82 is engaged by a shoulder 87 on the slide 27, the sear being thus withdrawn from the firing pin and the firing pin being thus released to move forward under the influence of the spring 81 and to effect firing of the cartridge.

For holding the slide 27 in its rear position as shown in Fig. 2 there is provided a second sear 88 pivoted to the bottom plate 5. This sear is spring pressed upward and engages a notch 89 in the bottom of the slide. Carried by the rear plate 6 is a manually operable trigger 90 having a tall portion 91 which projects forward through an opening in the plate and is adapted to engage the sear 88. A spring pressed plunger 92 tends to hold the trigger in its rearward inoperative position.

By referring to Fig. 2 it will be observed that when the slide 27 is held by the sear 86 the shoulder 85 on the firing pin is directly engaged by the shoulder 86 on the slide, the firing pin thus being firmly held entirely independently of the sear 82. This makes it impossible for the firing pin to be accidentally released by vibration or otherwise while the breech bolt is in its rear position.

In initially loading the gun in order to start firing it is ordinarily necessary to operate the

mechanism of the gun by hand in order to withdraw the first cartridge from the belt and transfer it into the position shown in Fig. 2. For this purpose there is provided a handle 93 extending through a slot 94 in the left side wall of the casing and fitting a hole 95 in the slide 27. The slot 94 is enlarged at its rear end and the handle 93 is so formed that it can be removed only when in register with the enlarged rear end of the slot.

From the foregoing description the operation of the gun will be readily understood and only a very brief summary is needed. When the trigger 90 is pressed forward the sear 88 is disengaged from the slide 27 and the slide moves forward, causing the several parts to assume the positions shown in Fig. 3. When these positions are reached the sear 82 is engaged by the shoulder 87 and is moved, thus releasing the firing pin 80 and causing firing. Thereupon the gases of explosion enter the cylinder 30 and drive the piston 29 rearward, thus moving the slide 27 rearward and causing the various parts of the gun to assume the relative positions shown in Fig. 2. During this rearward movement a new cartridge is extracted from the belt and the shell of the exploded cartridge is ejected in the manner already described. If, in the meantime, the trigger 90 has been released and permitted to resume its normal position, the slide is caught and held by the sear 88 and no further firing takes place. If, however, the trigger 90 is held in its forward firing position the parts immediately again move forward to the firing position shown in Fig. 3 and firing again occurs. Thus volley firing may be continued so long as the trigger 90 is held and so long as the supply of cartridges in the belt is not exhausted.

What I claim is:

1. The combination in an automatic firearm, of a barrel, a breech casing carrying the barrel and having a transverse cartridge feed channel therein immediately below the rear portion of the barrel, a movable breech bolt in the casing, a transversely movable cartridge feed slide below the feed channel, an operating slide below the feed slide automatically movable rearward upon firing connected with the breech bolt to move the same and having at the top thereof a cam path at least a part of which is inclined with respect to the direction of movement and which has a transversely unobstructed portion, and means on the bottom of the feed slide normally engaging the cam path to cause normal transverse movements of the feed slide, the last said means being readily separable transversely from the cam path when in register with the unobstructed portion thereof to permit the operating slide to be removed longitudinally from the casing independently of the feed slide.

2. The combination in an automatic firearm, of a barrel, a breech casing carrying the barrel and having a transverse cartridge feed channel therein immediately below the rear portion of the barrel, a movable breech bolt in the casing, a transversely movable cartridge feed slide below the feed channel, a cam path engaging means on the bottom of the feed slide, and an operating slide below the feed slide automatically movable rearward upon firing connected with the breech bolt to move the same and having at the top thereof a cam path which engages the said means on the bottom of the feed slide and at least a part of which is inclined with respect to the direction of movement of the operating

- slide so as to cause normal transverse movements of the feed slide, the said cam path serving when the operating slide is within its normal range of movement to retain engagement 5 with the engaging means on the bottom of the feed slide and the said cam path being transversely unobstructed at one end to permit disengagement of the said means therefrom when the operating slide is in an abnormal position.
- 10 3. An automatic firearm comprising in combination, a barrel, a breech casing carrying the barrel and having a transverse cartridge feed channel therein immediately below the rear portion of the barrel, a movable breech bolt in the casing, a transversely movable cartridge feed slide below the feed channel and removable transversely from the casing, a cam path engaging means on the bottom of the feed slide, and an operating slide below the feed slide automatically movable rearward upon firing connected with the breech bolt to move the same and having at the top thereof a cam path which engages the said means on the bottom of the feed slide and at least a part of which is inclined with respect to the direction of movement of the operating slide so as to cause normal transverse movements of the feed slide, the said cam path serving when the operating slide is within its normal range of movement to prevent 15 transverse removal of the feed slide from the casing and the said cam path being transversely unobstructed at one end to permit such removal when the operating slide is in an abnormal position.
- 20 35 4. In an automatic firearm, the combination of a barrel, a breech casing carrying the barrel and having a transverse cartridge feed channel therein below the level of the barrel, a breech bolt in the casing automatically movable rearward upon firing and having in the front thereof a vertical groove for receiving and retaining the heads of the cartridges, an extractor movable with the bolt and serving during successive rearward movements to extract successive cartridges 25 from the feed channel and to move each of them upward with its head in the said groove in front of the bolt, and a resiliently held detent on the bolt permitting free upward movement of each cartridge and automatically moving forward 30 under each cartridge to prevent downward movement thereof.
- 40 5. The combination in an automatic firearm, of a barrel, a breech casing carrying the barrel and having a transverse cartridge feed channel there- 45 in below the level of the barrel, a breech bolt in the casing automatically movable rearward upon firing and having in the front thereof a vertical groove for receiving and retaining the heads of the cartridges, an ejector carried by the bolt at a level above the firing position of the cartridges, an extractor movable with the bolt and serving during movements to extract successive cartridges 50 from the feed channel and to move each of them upward into firing position with its head in the said groove in the front of the bolt and also serving to move the shell of the next preceding cartridge upward into position to be engaged by the ejector, and means acting near the end of the rearward movement of the bolt for causing relative movement of the ejector to disengage the said cartridge shell from the bolt and eject it from the firearm.

6. The combination in an automatic firearm, of a barrel, a breech casing carrying the barrel and having a transverse cartridge feed channel therein below the level of the barrel, a breech bolt in the casing automatically movable rearward upon firing and having at the front thereof two rigid vertical ribs of different lengths and heights forming a vertical groove for receiving and retaining the heads of the cartridges, an ejector carried by the bolt above the end of the shorter rib, an extractor movable with the bolt and serving during movements to extract successive cartridges from the feed channel and to move each of them upward into firing position with its head in the said groove in the front of the bolt and also serving to move the shell of the next preceding cartridge upward out of engagement with the shorter rib while retaining engagement with the longer rib, and means acting near the end of the rearward movement of the bolt for relatively moving the ejector and thereby causing it in cooperation with the longer rib to eject the said cartridge shell from the firearm.

7. The combination in an automatic firearm, of a barrel, a breech casing carrying the barrel and having a transverse cartridge feed channel therein below the level of the barrel, a breech bolt in the casing automatically movable rearward upon firing and having at the front thereof two rigid vertical ribs of different lengths and heights forming a vertical groove for receiving and retaining the heads of the cartridges, an ejector carried by the bolt at the top thereof and having a hook portion above and in vertical register with the said shorter rib, an extractor movable with the bolt and serving during movements to extract successive cartridges from the feed channel and to move each of them upward into firing position with its head in the said groove in the front of the bolt and also serving to move the shell of the next preceding cartridge upward out of engagement with the shorter rib and into engagement with the hook portion of the extractor while retaining engagement with the longer rib, and means acting near the end of the rearward movement of the bolt for relatively moving the ejector and thereby causing it in cooperation with the longer rib to eject the said cartridge shell from the firearm.

8. In an automatic firearm the combination, of a barrel, a breech casing carrying the barrel and having a transverse cartridge feed channel therein below the level of the barrel, a breech bolt in the casing automatically movable rearward upon firing and having in the front thereof a vertical groove for receiving and retaining the heads of the cartridges, an ejector carried by the bolt at a level above the firing position of the cartridges, an extractor movable with the bolt and serving during movements to extract successive cartridges from the feed channel and to move each of them upward into firing position with its head in the said groove in the front of the bolt, and a lifter carried by the extractor and adapted to engage the shell of the next preceding cartridge to move it upward into position to be engaged by the ejector, and means acting near the end of the rearward movement of the bolt for causing relative movement of the ejector to disengage the said cartridge shell from the bolt and eject it from the firearm.

MARRINER A. BROWNING.
